UNITED STATES PATENT OFFICE

CHARLES A. MOORE, OF EDINA, MINNESOTA

AIR CONDITIONING DEVICE FOR COLD STORAGE ROOMS

Application filed March 19, 1930, Serial No. 437,012. Renewed April 30, 1931.

My invention relates to improvements in air conditioning devices for cold storage rooms.

An object of the invention is to provide a simple, durable and effective refrigerating means for a room capable of being constructed and installed at relatively small cost and adapted to ventilate the room and set up a convective and diffused circulation of the air therein.

With the foregoing and other objects in view, which will appear in the following description, the invention resides in the novel combination and arrangement of parts and in the details of construction hereinafter described and claimed.

In the drawings, Fig. 1 is a plan view of a device embodying my invention, the same being illustrated as applied to a cold storage room, the building structure forming the room being shown in section and taken as on the line 1—1 of Fig. 2; Fig. 2 is a view taken as on the line 2—2 of Fig. 1, said view showing the building structure in section and the device therein in plan; Fig. 3 is a sectional view taken on the line 3—3 of Fig. 1 and Fig. 4 is a fragmentary detail view showing one end of the coil bunker in plan, a portion of the bunker being broken away to disclose parts otherwise concealed.

Reference being had to the drawings, it will be seen that I have illustrated an embodiment of my invention in connection with a room A provided within a building structure, consisting of a floor 10, side walls 11, end walls 12 and ceiling 13, all of which may be insulated in any suitable manner. This room A, in accordance with the usual practice in connection with cold storage rooms, is elongated and of sufficient width laterally to provide lading spaces on opposite sides of a central trucking aisle. Within the upper portion of the room and overhead over this aisle, I arrange my improved air conditioning device which includes a bunker B. This bunker comprises sides 14, ends 15 and a bottom 16 having an elongated central port 17 therein stopping short at its ends of the ends 15 of the bunker. Said bunker B is a double-walled structure preferably formed of sheet metal,

the sides, ends and bottom being hollow to provide passageways within the interior thereof for the passage therethrough of a ventilating flow of air. In the spaces within the ends 15 and end portions of the bottom 16 are partition strips 18 and 19 which lie in a vertical plane medially longitudinally of the bunker structure. The spaces within the side 14 and ends 15 at one side of this plane communicate with each other and with the space within the bottom 16, at the same side of the plane, said latter bottom space being in communication with the interior of the room through openings 20 and 21 in the side and end portions of the bottom 16, along the edges of the port 17. At the other side of the plane in which partition strips 18 and 19 lie, the spaces within the side 14, ends 15 and bottom 16 intercommunicate, the spaces in said side and ends being in communication, along the upper edges thereof, with the interior of the room through openings 22 and 23.

It will be noted that the bunker B is spaced, not only from the sides of the room, but also from the ends thereof and from the ceiling, the entire bunker structure being suspended from the ceiling by means of hangers 24. Extending through one of the end walls 12 of the room structure is a fresh air ingress pipe 25 which communicates with the space within one of the ends 15 of the bunker at the uppermost portion of said end, said pipe being fitted with a damper 26. Extending through the other end wall 12 of the room structure is an air egress pipe 27 which communicates with the air space within the adjacent end 15 of the bunker at the lowermost portion of said end, said pipe being fitted with a damper 28.

Suspended by hanger straps 29, within the bunker B, is a coil 30, the turns thereof being arranged in tiers positioned over the side and end portions of the bottom 16. This coil conveys therethrough a suitable circulating refrigerating medium.

The air within the bunker B and about the coil 30, being refrigerated by reason of the refrigerating medium circulating through said coil, descends by gravity passing downwardly through the port 17 in the bunker

B to the floor of the room A where the flow of air divides and moves toward the relatively warm sides of the room along which the air ascends to the ceiling. Thence, the air travels inwardly from the sides 11 of the room passing through the spaces 31 between the upper edges of the sides 14 of the bunker to position over the coil 30 where the downward movement of the air is again effected. 5 While the circulation of air within the room is, in the main, as above described, it is to be noted that there will be at either end of the room an upward movement of air along the ends 12 of the building structure. At 10 the ceiling this flow of air passes inwardly into the upper portion of the bunker B, passing through the spaces 32 between the ends 15 of the bunker structure and the ceiling 13 of the room. 15 The side and end portions of the bottom 16 about the port 17 slope inwardly and upwardly, the entire bunker structure being tilted slightly endwise. At the lower end of the bunker, I arrange a drain pipe 33. 20 This pipe carries away whatever condensation may accumulate within the spaces between the double walls of the bunker structure. Also, whatever condensation may accumulate on the inner surfaces of the bunker 25 and whatever drip there may be from the coil 30 to the bottom 16 of the bunker, there being an aperture 34 provided in the inner wall of the bottom 16 of the bunker for the passage of water therethrough to the space 30 within said hollow bottom. In this connection it will be understood that the upstanding partition strip 18 in the depressed end of the bunker is cut short or notched slightly at the bottom thereof to permit of the 35 passage of water from the space in the bottom 16 at the side of the plane of the partition strips opposite the point of connection of the drain pipe 33 to the corresponding space at the other side of said plane. 40 From the foregoing, it will be understood that my improved device creates an internal convective and diffused circulation of air within the room by gravity. In addition thereto is created a ventilating circulation 45 of air by gravity, the two acting in aid of each other. Air in the passageway formed by the spaces in one side 14, the ends 15 and bottom 16 at one side of the plane of the partition strips 18, 19, is cooled by the refrigerated air within the bunker B. Thus 50 cooled, the air in said passageway flows into the interior of the room along the port 17 of the bunker, through the openings 20 and 21 in the side and end portions of the bottom 16, fresh air from the outside being admitted through the pipe 25, under control of the damper 26, to the space within the connected end 15 of the bunker, near the upper edge of said end. The fresh air thus introduced into the room by gravity joins the 55 descending flow of air at the port 17. The air within the passageway formed by one side 14 and the ends 15 and bottom 16 of the bunker at the opposite side of the plane of said partition strips, is cooled by reason of the presence of refrigerated air within the bunker, and gravitates to the outside through the air egress pipe 27, under control of the damper 28, the air within said side 14 and intercommunicating parts of the bunker being replaced with air from the interior of the room near the ceiling, such air entering the spaces within said side 14 and the ends 15 through the openings 22 and 23 therein. Thus is instituted a ventilating circulation 60 of air, the air exhausted being taken from the upper portion of the room where it is of highest temperature. 65 Changes in the specific form of my invention, as herein disclosed, may be made within the scope of what is claimed without departing from the spirit of my invention. 70 Having described my invention, what I claim as new and desire to protect by Letters Patent is: 75

1. The combination with a structure forming a room, of an elongated coil bunker located centrally of the room at its upper portion and spaced from the ceiling, sides and ends thereof, said bunker comprising a double walled structure including hollow sides, hollow ends and a hollow bottom formed with a central longitudinal port therein falling short at its extremities of said ends, said bottom sloping downward toward said sides and ends from the edges of said port, partition strips within the hollow bottom at either end thereof and similar strips within the hollow ends, said strips lying in a medial vertical plane longitudinally of said bunker, the hollow space in one of said sides communicating with the hollow spaces within both ends and with the hollow space within the bottom, said spaces within said ends and bottom opening at one side of said partition strips into the interior of the room along the adjacent edges of said port, a pipe entering the room from without and communicating with the interior of one of said ends near its upper portion at said side of said strips, the hollow space within the other of said sides being in communication with the hollow spaces within the ends and bottom at the corresponding side of said partition strips, said spaces within said last mentioned side and ends being in communication with the interior of the room along the upper edges of said sides and ends, an egress pipe communicating with the interior of one of said ends near the lower portion thereof and at said latter side of said partition strips, said egress pipe issuing from the room, a drain pipe leading from the bottom of the bunker, and a pipe for a refrigerant coiled in elongated formation, turn upon turn, within said 100

bunker, the tiers of pipe reaching along the sides of the coil and the ends thereof being disposed above the bottom of the bunker along its sides and ends.

- 5 2. The combination with a structure forming a room, of an elongated bunker located centrally of the room at its upper portion and spaced from the ceiling, sides and ends thereof, said bunker comprising a double walled structure including hollow sides, hollow ends and a hollow bottom formed with a central longitudinal port therein, partition strips within the hollow ends, said strips lying in a medial vertical plane longitudinally of said bunker, the hollow space in one of said sides communicating with the hollow spaces within both ends and with the hollow space within the bottom, said spaces within said ends and bottom opening at one side of said partition strips into the interior of the room along one side of said port, a pipe entering the room from without and communicating with the interior of one of said ends near its upper portion at said side of said strips, the hollow space within the other of said sides being in communication with the hollow spaces within the ends and bottom at the corresponding side of said partition strips, said spaces within said last mentioned side and ends being in communication with the interior of the room along the upper edges of said sides and ends, an egress pipe communicating with the interior of one of said ends near the lower portion thereof and at said latter side of said partition strips, said egress pipe issuing from the room, and a conduit for a circulating refrigerant disposed within the bunker.
3. The combination with a structure forming a room, of an elongated bunker located at the upper portion of the room and spaced from the ceiling, ends and sides thereof, said bunker comprising a structure consisting of sides, ends and a bottom, the sides and bottom being hollow and the latter formed with a central longitudinal port therein, the hollow space in one of said sides communicating with the hollow space in the adjacent bottom portion, said latter space opening into the interior of the room along the edge of said port, means for conducting fresh air from without into the space within said side at the upper portion thereof, the hollow space within the other of said sides being in communication with the hollow space within the adjacent bottom portion, said latter space opening into the interior of the room along the upper edge of said side, means for conducting air to the outside of the room from said last mentioned bottom portion, and refrigerating means disposed within the bunker.

4. The combination with a structure forming a room, of an elongated bunker located at the upper portion of the room and spaced from the ceiling, ends and sides thereof, said bunker comprising a structure consisting of

sides, ends and a bottom, the sides and bottom being hollow and the latter formed with a central longitudinal port therein, the hollow space in one of said sides communicating with the hollow space in the adjacent bottom portion, said latter space opening into the interior of the room along the edge of said port, means for conducting fresh air from without into the space within said side at the upper portion thereof, the hollow space within the other of said sides being in communication with the hollow space within the adjacent bottom portion, said latter space opening into the interior of the room along the upper edge of said side, valved means for conducting air to the outside of the room from said last mentioned bottom portion, and refrigerating means disposed within the bunker.

5. The combination with a structure forming a room, of an elongated bunker located at the upper portion of the room and spaced from the ceiling, ends and sides thereof, said bunker comprising ends, hollow sides and a hollow bottom formed with a central longitudinal port therein, refrigerating means within the bunker, means for introducing fresh air from the outer atmosphere into one of the hollow sides, the space within said side and the space within the adjacent portion of the bottom forming a passageway for the fresh air opening into the interior of the room along said port, the space within the other side forming a passageway for air from the upper portion of the room along the upper edge of said side to the space within the adjacent bottom portion, and means for conducting the air from the interior of said last mentioned bottom portion to the outer atmosphere.

6. The combination with a structure forming a room, of a bunker located in the upper portion of the room, refrigerating means disposed within the bunker, said bunker having hollow walls forming passageways, one passageway having an air egress opening at the lower portion of bunker and the other having an air ingress opening at the upper portion thereof, means for introducing air from the outer atmosphere into said first passageway at an elevation above said air egress opening, and means for conducting air to the outer atmosphere from said second passageway at an elevation below said air ingress opening.

7. In a refrigerator, a cabinet providing a chamber and having a door lending access thereto, a bunker structure in the upper portion of the chamber, a refrigerating element disposed within the bunker structure, said structure comprising hollow baffles coextensively disposed and each consisting of a side member and a bottom member, the bottom members being spaced apart at their inner extremities to form a central air egress port,

said baffles being spaced from the ceiling of the chamber at the upper extremities of their side members to admit air to the upper portion of the bunker from the upper portion of
5 said chamber at either side of the bunker, the interior of one of the side members communicating at its upper portion with the outer air, its respective bottom portion communicating along the inner edge thereof with
10 the interior of the chamber at said port, the interior of the other side member communicating along the upper extremity of said member with the interior of the chamber, the respective bottom portion of said last
15 member communicating with the outer air.

8. In a refrigerator, a cabinet providing a chamber, a bunker structure in the upper portion of the chamber, a refrigerating element disposed within the bunker structure,
20 said structure including upright hollow baffles coextensively disposed and spaced from the ceiling of the chamber at their upper extremities to admit air to the upper portion of the bunker from the upper portion of
25 said chamber at either side of the bunker, the interior of one of the baffles being in communication at its upper portion with the outer air and at a lower portion with the interior of the chamber, the interior of the
30 other baffle being in communication at its upper portion with the interior of the chamber and at a lower portion with the outer air.

In testimony whereof I have affixed my
35 signature to this specification.

CHARLES A. MOORE.
